UNITED STATES PATENT OFFICE.

JACOB P. WRIGHT, OF BARBERTON, OHIO, ASSIGNOR TO THE DIAMOND MATCH COMPANY, OF CHICAGO, ILLINOIS, A CORPORATION OF ILLINOIS.

BOX-FILLING MACHINE.

1,014,356.

Specification of Letters Patent.

Patented Jan. 9, 1912.

Application filed May 28, 1909. Serial No. 498,858.

To all whom it may concern:

Be it known that I, JACOB P. WRIGHT, a citizen of the United States, and resident of Barberton, in the county of Summit and State of Ohio, have invented certain new and useful Improvements in Box-Filling Machines, of which the following is a specification.

This invention relates to an improvement 10 in box filling machines, having reference to machines for opening, filling and closing the tray-and-shuck form of box commonly employed for holding matches, such, for example, as set out in Letters Patent of the 15 United States No. 836,730, dated November 27, 1906.

The present improvement is more particularly directed to the box-carrying chain of the said patented machine, which chain 20 comprises jointed links of appropriate shape and size provided with suitably arranged walls or jaws between which closed boxes are deposited and thereby grasped and transported to and across the path of plunger 25 mechanism by means of which the trays are partially pushed endwise from their shucks into position to receive the matches from a suitable source of supply; the boxes, with their open filled trays, being thereafter 30 transported to plunger devices by means of which the trays are pushed into their shucks.

In the chain structure illustrated in the patent aforesaid, the shuck and tray receiving portions of the links correspond respectively with the dimensions of the particular shucks and trays to be introduced thereto, the inner ends of the bottom and side walls of each tray receiving portion of the link thus affording for the opposing edge of 40 the proximate shuck a stop or abutment to prevent the inward movement of the shuck when the tray is being pushed endwise therefrom. Owing to the thickness and inequalities of shuck material, it is necessary that 45 the abutments to subserve their function in the individual links, should be formed with uniformity and precision throughout, and hence, as the chain in its entirety comprises numerous links, it follows that superior care 50 and skill, with attendant expense, are required to produce the same.

The primary object of the present invention is to simplify the construction of the box-carrying chain; and to this end, I provide in lieu of the integral shoulders of the

individual links, an independent abutment member which extends constantly within and longitudinally of the path of the chain in such manner that as the boxes are transported in respect to the plunger mechanism 60 the inner ends of the box shucks take progressively against the said member and are thereby effectually prevented from being moved transversely of the chain during the opening of the trays by the plungers. In 65 pursuance of my invention I also provide a pressure device which acts upon the boxes during their travel and insures their engagement with the abutment irrespective of inequalities of thickness of the shuck material, all of which will be hereinafter fully 70 described and claimed.

In the drawings—Figure 1 is a plan of a part of a box-filling machine embodying a good form of my invention. Fig. 2 is a 75 transverse section, enlarged, as on the line 2—2 of Fig. 1. Fig. 3 is a longitudinal vertical section, as on the line 3—3 of Fig. 2. Fig. 4 is a perspective of several links of the box-carrying chain showing the longitudinally-extending abutment bar therein. Fig. 5 is a partial transverse section, showing a 80 modification of the abutment device for the ends of the box-shucks while the trays are being pushed endwise therefrom within the 85 carrier. Fig. 6 is a view of the underside of one of the spring actuated abutment blocks shown in Fig. 5.

1 designates a part of the upper traveling portion of the endless carrier by means of 90 which the boxes are transported, which carrier comprises a chain having hingedly connected links 2 provided with suitably located walls 3, which constitute in effect jaws. As the links pass around a sprocket wheel at one 95 end of the machine bed, the jaws of the adjoining links are opened or diverged by the flexing of the chain, and the closed boxes are pushed laterally from a superposed hopper and dropped down between the jaws. 100 When the links in their traverse assume a horizontal course their jaws grasp the interposed boxes and transport them across the path of a series of horizontally-reciprocating plungers 4, by means of which the box-trays 105 (a) are pushed endwise almost entirely out of their shucks (b). The plungers are slid- 110 ingly mounted in guides transversely of an endless chain 5, and are provided at their outer ends with depending studs 6 which

engage a horizontal cam-way 7 in a bar 8 affixed to the bed; such cam-way being appropriately formed to effect the timely reciprocations of the successive plungers. The 5 portions of the walls between which the trays are pushed may be made slightly thicker than the portions between which the shucks are held, so as to correspond with the lesser width of the trays, in which case the 10 receiving end of the thicker walls should be beveled or reduced in thickness in order to permit the free and unobstructed entrance there-between of the trays as they are pushed from their shucks.

15 In the floor of the chain links is a medial groove or channel 9, which extends longitudinally of the path of the chain, the walls of the links being cut away vertically above the groove or channel. When the links are 20 passing the series of tray-ejecting plungers 4 the groove or channel receives lengthwise thereof a stationary horizontal bar 10 the top of which, excepting its rearward edge, is on a level with the floor of the links. This 25 rearward edge is provided with a longitudinal lip 11, of a height corresponding with the thickness of the bottom of the shuck, or substantially so, so as to afford a determinate abutment for the latter when the tray 30 is being pushed outward from the shuck by the plungers. The abutment bar is formed on or secured to a bracket 12 affixed to the cap plate 13. As herein illustrated, this bar 35 may be conveniently provided by forming the lip 11 upon the straight or plain portion of the longitudinal cam-bar which is employed for canting the open tray in the machine of the patent aforesaid.

To insure the efficient contact of the inner 40 ends of the individual shucks with the lip of the abutment bar, during their travel, I preferably secure to the fixed cap plate 13 one edge of a spring plate 14, the opposite edge of which is equipped with a series of 45 blocks or shoes 15 which extend through a longitudinal slot in the cap plate and bear yieldingly upon the boxes carried thereunder by the chain 1. This plate is split or divided transversely for the greater part of its 50 width to afford a series of independent spring members each bearing a block whose forward corner is beveled or rounded, as at 16, to permit the ready passage thereunder of the traveling boxes.

55 In Figs. 5 and 6 is shown a modification of the invention, wherein the lip 11 constituting the abutment for the shucks, instead of being formed on the cam bar, is provided on the under sides of the spring supported 60 blocks or shoes 15 so as to depend along the upper inner edges of the shucks while the trays are being pushed open by the successively acting plungers. A lip is formed on

each of the blocks in order that the abutment thereby afforded will adapt itself to the 65 slight variances in the opposing ends of the shucks, and the ends of the several lips are preferably beveled as indicated to facilitate the passage of the shucks thereto. In this modified form, as in the first described construction, the abutment constituted by the 70 lip extends longitudinally of the path of travel of the carrier and constantly into the plane of the inner ends of the progressively advancing shucks; and also by virtue of the 75 spring feature a relative adjustment is effected between the abutment member and the boxes to insure their inter-engagement irrespective of slight variances in the dimensions of the shucks. 80

I claim—

1. In a box filling machine, the combination of a box carrier for tray-and-shuck boxes, said carrier being provided with a longitudinal groove or channel in the floor 85 thereof, a stationary bar extending into said groove or channel and having a lip or projection above the plane of the floor of the carrier, and a spring member bearing upon the box-shucks. 90

2. In a box filling machine, the combination of a carrier for tray-and-shuck boxes, means for pushing the box-trays endwise from their shucks within and transversely of the carrier, and a series of independent pressure devices bearing yieldingly upon the 95 box shucks while the trays are being pushed therefrom.

3. In a box filling machine, the combination of a carrier for tray-and-shuck boxes, 100 means for pushing the box-trays endwise from their shucks within and transversely of the carrier, a spring member provided with blocks or shoes which bear upon the box shucks within the carrier, while the 105 trays are being pushed therefrom, and an abutment extending into the plane of the inner ends of the said shucks.

4. In a box filling machine, the combination of a carrier for tray-and-shuck boxes, 110 means for pushing the box-trays endwise from their shucks within and transversely of the carrier, a spring plate divided to form a series of independent spring members which overhang the carrier, and a series of 115 pressure blocks carried by said members and adapted to bear upon the box-shucks while the trays are being pushed therefrom.

Signed at Barberton in the county of Summit and State of Ohio this 24th day of 120 May 1909.

JACOB P. WRIGHT.
